UNITED STATES PATENT OFFICE.

HENRY T. HAZARD, OF LOS ANGELES, CALIFORNIA.

MEASURING DEVICE FOR SHOT-POUCHES, POWDER-FLASKS, &c.

SPECIFICATION forming part of Letters Patent No. 276,690, dated May 1, 1883.

Application filed February 14, 1882. (No model.)

To all whom it may concern:

Be it known that I, HENRY THOMAS HAZARD, of Los Angeles, in the county of Los Angeles and State of California, have invented 5 a new and useful Improvement in Cut-Offs or Measuring Devices for Use on Shot-Pouches or Powder-Flasks, of which the following is a specification.

Heretofore the cut-offs used on shot-pouches 10 consisted of a lever on either end of which is attached a cut-off, which lever is pivoted in its center to the tube which contains the shot, and is operated by the thumb, as shown in Figure 5 of the drawings. This manner of operating a cut-off is objectionable in this, that the moment it begins to cut off the shot or powder in the tube above, the lower cut-off commences to retreat and open the channel below, thereby permitting the contents to run out before it is entirely cut off above; hence if the 15 lever is operated slowly a larger quantity is permitted to pass out than if operated rapidly, and if the upper end of the lever should be suspended when one-half the way in, then the lower cut-off would be arrested while one-half out; hence a continuous opening is permitted clear into the pouch or flask, whereby an unlimited quantity of shot or powder might thus be deposited. This position of the lever is 20 shown in Fig. 5. It is the liability to do this that has rendered this character of a cut-off so dangerous as to prevent its general use as a cut-off for powder. It is further objectionable as a shot cut-off, because as the upper end of 25 the lever enters the tube containing the shot it may be arrested by contact with the shot, thereby permitting the lower cut-off to move out, and hence the charge cannot pass out. This will frequently occur when large shot are 30 being used; and if the shot is small, then the objection of having too much shot pass out at each charge, or in irregular quantities, will occur. By my improvement here shown those 35 defects cannot exist, as the upper cut-off will have entered completely into and cut off the channel above before there is any opening whatever below, so that whether operated slowly or rapidly the same amount is deposited 40 at each movement of the thumb, and if, in entering, the upper cut-off should be arrested by the unyielding substances—such as shot in the

measuring-tube—then the cut-off below will instantly recede and permit the charge to pass out, and at no time is there an opening clear through the measuring-tube. The novel manner in which this is effected will be apparent by means of the accompanying drawings— 55

Fig. 1 being side view of my improved cut-off in its natural position while at rest; Fig. 2, position when the upper cut-off has advanced 60 and divided the charge, and before the lower cut-off is opened, a perfect charge being now contained in the measuring-tube between the two cut-offs; Fig. 3, a top view, and Fig. 4 a modification, of same, Fig. 5 being ordinary 65 shot cut-off now in common use; and Fig. 6 is a front and side view of the cut-off E.

In the drawings, A is the flask, pouch, or other reservoir; B, the measuring-tube; I, the operating-lever; F, the upper and E the lower 70 cut-off; D, the operating spring, the recoil of which will return the lever to its natural position. The thumb-piece is at the point on lever marked C. H of Fig. 4 is a spring that bears down against the lower cut-off, E, and 75 keeps same closed when at rest; and H' of same figure is a spring, the recoil of which keeps the upper cut-off, F, open when at rest. Said springs are rigidly attached at the points indicated by screw-heads. The lower cut-off, 80 E, has a hook, N, mounted on its free end, the object of which is to prevent the cut-off from receding clear out of the measuring-tube, and at same time to leave a complete opening therein. This hook is shown in detail in Fig. 9. A 85 uniformity of openings in the measuring-tube is thereby secured.

In the ordinary lever cut-off the outward movement of the lower cut-off, E, is only arrested when the upper end of the lever, which 90 is beneath the thumb, comes in contact with the measuring-tube or other fixed stop for that end of the lever, so that, as the charge is to be decreased or increased, the lower cut-off is correspondingly brought closer to or removed farther 95 from the center, where the lever is pivoted, and as it approaches the center it does not open so far as it does when farther from the center. Therefore it is not uniform in the opening through which the substance to be measured 100 passes.

The advantages here shown will render these

devices invaluable in loading cartridge-shells with powder and shot in place of the open scoop now in use.

What I claim is—

- 5 1. The shot-charging device consisting, substantially as shown, of the operating-lever I, terminating on either side of the measuring-tube, as shown, to which are pivoted the cut-off gates E and F, in connection with the spring D, which holds the lever in position, the slotted measuring-tube B, having a uniform diameter leading directly into the shot-reservoir, the cut-off gate E being pivoted to the lower end of the lever, and the gate F being pivoted to the upper rear end of said lever, and on which end is formed a thumb-piece, C, the cut-off F having a stationary passage-way at the mouth of the shot-reservoir, in which said gate works transversely to the measuring-tube through which it passes, forming a fulcrum for the lever I when the gate stops by reason of its contact with the inside of the tube, or of the substance therein, whereby the channel above is completely closed before the 25 channel is opened below.
- 15 2. In a measuring device or cut-off having a tube to contain the substance to be measured, the combination therewith of the lever I, having thereto attached the cut-offs E and F and the spring D, the cut-off E being provided with a hook or stop, N, projecting from the free end thereof, substantially as described.
- 20 3. In a shot or powder measuring device or cut-off, the combination, with the measuring-tube B, of an operating-lever so constructed that the ends of said lever terminate on opposite sides of said tube, and to either end of

which lever is pivoted a cut-off gate, and the spring D, whereby as the said lever is operated the upper cut-off closes the channel above before any opening is permitted below, substantially as and for the purpose described.

4. The measuring-tube B, having slots to admit the cut-off gates E and F, in combination with the lever I, terminating on opposite sides of said measuring-tube, the cut-off gates E and F, E having the stop or lug N affixed to the free end thereof and pivoted to the lower arm of said lever, the cut-off gate F being pivoted to the upper arm of said lever and forming a fulcrum for said lever, and having stationary guideways arranged at the mouth of the pouch or flask for its reception and operation, and the spring D, substantially as and for the purpose shown and described.

5. In a shot or powder measuring device or charger, the tube B, containing the substance to be measured, having slots on opposite sides for the reception and operation of the cut-offs E and F, in combination with the lever I, which extends around said tube in the manner shown, and the spring D, the cut-off F being pivoted to said lever above and beneath the thumb-piece C, and the cut-off E being pivoted to the lower end of said lever on the opposite side of the tube, whereby the channel in the upper part of the tube is closed by the pressure on the thumb-piece before the lower cut-off, E, recedes or moves out to open the channel below.

HENRY T. HAZARD.
